A. J. SAVAGE

FIREARM

Filed Sept. 10, 1919

Inventor:

Arthur J. Savage;
By Raymond S. Blakely,
Attorney.

Patented June 16, 1925.

1,542,477

UNITED STATES PATENT OFFICE.

ARTHUR J. SAVAGE, OF SAN DIEGO, CALIFORNIA.

FIREARM.

Application filed September 10, 1919. Serial No. 322,903.

To all whom it may concern:

Be it known that I, ARTHUR J. SAVAGE, a citizen of the United States, residing at San Diego, in the county of San Diego and State 5 of California, have invented new and useful Improvements in Firearms, of which the following is a specification.

This invention relates to fire arms, and more particularly to rifles of the single-shot type, and it has for its object to provide an improved fire arm of the general character stated which will be superior in point of relative simplicity and inexpensiveness of construction taken in conjunction with safety and efficiency in operation, quickness in loading and shell ejection, and positiveness and general superiority in performance and operation.

With the above and other objects in view,
20 the invention consists in the novel and useful provision, formation, combination, association, cooperation and inter-relation of parts, members and features, all as herein-after described, shown in the drawing and
25 finally pointed out in claims.

In the drawing:

Figure 1 is a longitudinal vertical section-al view, partly broken away for clearness of illustration, of a fire arm constructed and 30 organized in accordance with the invention, the breech bolt being shown in forward position and the firing pin in firing position;

Figure 2 is a similar view showing the bolt in retracted position, and also the firing pin, and showing the position and condition of the parts when the exploded shell is being ejected;

Figure 3 shows the breech bolt and loading platform, fragmentarily, and in detached position, partially in section, and the loaded cartridge being about to be introduced within the barrel;

Figure 4 is a top plan view of the barrel and breech bolt, the latter being shown in forward or firing position;

Figure 5 is a vertical fragmentary transverse sectional view, taken upon the line x^6-x^6 , Figure 1;

Figure 6 is a vertical transverse sectional view taken upon the line x^6-x^6 , Figure 1;

Figure 7 is a side elevation of the rear sight which is arranged upon the barrel, part of the barrel being shown in conjunction therewith:

55 Figure 8 is a top plan view of the parts shown in Figure 7;

Figure 9 is a rear end view of the sight as shown in Figures 7 and 8;

Figure 10 is a side elevation of the trigger shown in combination with the other parts in Figure 2, the same being in detached position; and,

Figure 11 is a fragmentary vertical sectional view, taken upon the plane of the section in Figure 1, and showing the co-action of the sear and firing pin and trigger, when the firing pin is cocked and ready to be released by manipulation of the trigger. 65

Corresponding parts in all the figures are designated by the same reference characters. 70

Referring with particularity to the drawing, A designates the barrel of a rifle which is provided at its rearward end with a suitable chamber for the reciprocating breech bolt C. The barrel is supported by the

bolt C. The barrel is supported by the stock b, and is connected therewith by the take-down screw 12. The stock is provided with the usual grip 13. A cut-away portion or opening 14 is between the rearward end of the barrel and the forward end of the rearward barrel extension or housing 15.

forward barrel extension or housing 13, which is, as stated, mounted on the stock to accommodate the reciprocating breech bolt, reduced at its forward end, and provides an ejection opening for exploded shells, and likewise accommodates the insertion of loaded cartridges in a position to be forced into

cartridges in a position to be forced into the barrel upon the forward movement of the breech bolt. Within the breech bolt, which is tubular, is the longitudinally moving tubular firing pin *d*, which firing pin houses the main spring *e* between its front end and the retaining pin *f*. The breech bolt

C is locked ready for firing by turning it through the agency of the breech bolt handle 16, so as to bring it behind a shoulder 16^a in the housing 15, in accordance with ordinary military bolt action fire-arms practice. The bolt is then locked.

The firing pin *d* is cocked by manually drawing rearwardly the knurled head 17 fastened to the firing pin by means of a holding pin 18. This puts the main spring *e* under compression, the retaining pin *f* being accom- 100

pression, the retaining pin γ being accommodated, in the travel of the firing pin d , by an elongated slot 19. The main spring e 105 is thus positioned between the retaining pin

f and the forward end of the tubular firing pin *d*, acting in its expansion to carry forward the firing pin, with its operative nose 20, so as to bring such nose into firing engagement with the loaded cartridge 21 in position in the barrel. 110

- The firing pin is held in rearward or retracted position prior to firing, by the sear D, which is pivoted on the pin 22, and the sear is held in this position by the action of the trigger E, pivotally mounted as at 23 and having a nose 23^a entering a recess 23^b in the sear. The trigger and sear are held in these cooperative relations by the trigger spring 24. The trigger and sear and trigger spring 24 are accommodated in the usual manner in a suitable chamber 25 produced vertically through the stock 6, and the trigger projects beneath the stock, where it is enclosed within the usual trigger guard 26.
- When the trigger is pressed by the finger of the operator, the spring 24 is compressed, the trigger is oscillated upon its supporting pivot pin 23, the nose 23^a is depressed in rocking engagement with the sear D in the recess 23^b, and the sear is depressed so as to withdraw it from engagement with the firing pin and permit the firing pin to execute its firing motion under urging of the main spring e.
- As the breech bolt handle 16 leaves the housing 15 entirely upon rearward travel of the bolt C, it is necessary that the bolt be guided to keep the said bolt from rotating on its longitudinal axis and thus getting out of alignment, or bringing its associated parts out of alignment. To accomplish this, I provide a trigger extension 27 which is received within a groove 27^a in the under side of the breech bolt and prevents the bolt from turning. This trigger extension is directly over the trigger pin 23, and the groove 27^a extends the entire length of the bolt in the lower walls thereof and permits the bolt to be removed for cleaning, etc.
- The bolt-carrier extractor F, in conjunction with the trigger-and-sear combination, under pressure of the spring 24, ejects the cartridge case, or exploded shell, 28, through the cooperation of the shell rim and the upper surface of the sear D. It is to be particularly noted that the sear is provided with a beveled shoulder or face 22^a. This beveled face or shoulder acts to eject the shells. Without this face 22^a the shells would not eject and the arm would be of no use.
- The entering of the cartridge into the barrel chamber is accomplished by means of the loading platform 29, particularly shown in Figure 3, which is beveled or rounded at its rear end to guide the cartridge into position to align it with or register it with the barrel chamber.
- It is further provided that the trigger act as a lock to prevent rotation of the breech bolt C prior to firing of the gun when the gun is cocked. To this end I provide the trigger with a locking key 30 upon its forward portion, above the nose 23^a, and this fits into a corresponding slot in the breech

bolt. When the trigger is operated to release the firing pin, the key 30 is withdrawn from this accommodating slot, thus permitting rotation of the breech bolt. The key 30 is withheld from the said slot after the firing action, so that the bolt C can be rotated, by the sear which acts to that end upon the trigger under downward pressure of the advanced firing pin.

The breech bolt C is stopped in its rearward movement by the co-action of the key 30, at its forward end, with a rearwardly facing shoulder 30^a on the breech bolt.

To remove the breech bolt C, all that is required is to draw these last mentioned co-acting shoulders apart by pressing upon the trigger, whereupon the breech bolt may be rearwardly moved.

It is obvious that the fire arm can be readily taken apart or taken down by loosening the thumb screw or take-down screw 12 by its head 31 and thus removing the stock from the barrel.

The rear sight is constructed so that quick vertical adjustment may be obtained by rotating the knurled nut 32 which is threaded to the eye piece 33 having the peep aperture or opening 34. The sight base is fastened to the barrel by means of a screw 35. A tension is maintained at all times on the knurled nut 32 by means of a leaf spring 36, one end of which is held by the screw 35 and the free end of which presses on the nut. Protecting walls 37 are arranged at the sides of the sight, shielding and protecting the adjustable eye piece 33 from blows or knocks that might disengage it or interfere with its true alignment and proper mounting and disposition. It is obvious that these may be shaped in any desired fashion to more or less completely surround and house the eye piece with its peep opening.

It is obvious that many variations and modifications and alterations may be made with respect to the construction and interrelation of parts and features herein described and shown in the drawing, all without departing from the true spirit of the invention and a proper interpretation of the following claims:

Having thus disclosed my invention I claim and desire to secure by Letters Patent:

1. In a fire arm, the combination, with a barrel provided with a rearward extension, a breech bolt movably mounted in the barrel extension, a pivoted spring-pressed trigger, and a sear provided with a beveled shoulder and operatively associated with the trigger to be lifted in the path of the exploded shell, and a shoulder on the trigger formed and disposed in position to limit a rearward movement of the breech bolt.

2. In a fire arm, the combination with a barrel; of a reciprocating breech bolt, a

- trigger, a pivoted sear operated by the trigger, a firing pin mounted to reciprocate in the breech bolt, the sear being disposed in position to engage with the firing pin to hold it in retracted position, and means upon the trigger cooperating with the breech bolt to hold it locked against rotation when the sear is engaged with the firing pin; the breech bolt being released from such locked condition by actuation of the sear due to the movement of the sear by the firing movement of the trigger. 5 50
3. In a fire arm, the combination, with a barrel having a rearward extension; of a cartridge platform formed at the forward end of the extension to guide a cartridge into the barrel, a spring-pressed trigger pivotally mounted adjacent the barrel extension, and a separate sear formed with a bevel 10 55 adapted to eject a cartridge, said sear being adapted to engage with the spring-pressed trigger.
4. In a fire arm, the combination, with a reciprocating breech bolt; of a pivoted sear, and a pivoted spring-pressed trigger cooperating with the sear and adapted to actuate the sear; the trigger cooperating with the breech bolt to provide a stop for rearward movement thereof, said sear likewise being formed with a beveled shoulder 20 60 adapted to engage a cartridge for the ejection thereof.
5. A fire arm including a barrel, a reciprocating and rotating breech bolt mounted at one end of the barrel and having a slot, a pivoted sear, a pivoted trigger interlocked with the sear, a spring for tensioning said trigger, a key on the trigger adapted to engage in the slot when the sear is elevated 25 65 by the trigger and said key adapted to be shifted out of the slot when the trigger is pulled to release the sear.
6. A fire arm including a barrel, a barrel extension, a breech bolt rotatably and slidably mounted within the barrel extension and having a slot, a firing pin within the bolt, a pivoted sear adapted for engagement with the firing pin when the same is 30 70 75
- retracted, a cartridge ejecting shoulder carried by the sear, a trigger having an interlocking engagement with the sear, and a key on the trigger and adapted for engagement with the slot when the sear engages with the firing pin. 50
7. A fire arm including a breech bolt having a slot, a spring controlled firing pin 10 55 60 65 70 75 80 85 90 95 100
- slidable in the bolt and partly exposed through said slot, a trigger, a key on said trigger, a pivoted sear interlocked with the trigger and adapted to engage the firing pin when the latter is retracted, thereby permitting the key on the trigger to engage in said slot.
8. A fire arm including a breech bolt having a slot, a spring controlled firing pin 60 65 70 75 80 85 90 95 100
- slidable in the bolt and partly exposed through said slot, a spring pressed pivoted trigger arranged beneath the bolt, a key on said trigger, a pivoted sear interlocked with the forward end of said trigger and adapted to be lifted by the trigger when the firing pin is retracted to hold the same in restrained position, the said key lying within the slot when the sear is lifted.
9. A fire arm including a breech bolt having a slot, a spring controlled firing pin 70 75 80 85 90 95 100
- slidable in the bolt and partly exposed through said slot, a spring pressed pivoted trigger, a pivoted sear interlocked with the trigger and adapted to be lifted thereby when the firing pin is retracted and also adapted to be depressed when the trigger is pulled to release the firing pin, and a cartridge ejecting shoulder carried by the sear and adapted to be projected upwardly into contact with the firing pin and thereby disposed in the path of the rearwardly traveling shell when the bolt is pulled backwardly.

In testimony whereof, I have signed my name to this specification in the presence of two subscribing witnesses.

ARTHUR J. SAVAGE.
